UNITED STATES PATENT OFFICE.

ALBERT P. LEE, OF CHICAGO, ILLINOIS, ASSIGNOR TO LEE TRAILER AND BODY COMPANY, OF CHICAGO, ILLINOIS.

REAR-DUMP VEHICLE.

1,402,300.

Specification of Letters Patent. Patented Jan. 3, 1922.

Application filed July 28, 1920. Serial No. 399,519.

To all whom it may concern:

Be it known that I, ALBERT P. LEE, a citizen of the United States, residing at Chicago, in the county of Cook and State of Illinois, have invented a certain new and useful Improvement in Rear-Dump Vehicles, of which the following is a full, clear, concise, and exact description, reference being had to the accompanying drawings, 10 forming a part of this specification.

This invention relates to rear dump vehicles, and more particularly to vehicles provided with rear dump rolling hoppers, adapted to roll substantially automatically 15 from charge receiving to discharge position.

More particularly the invention relates to a rear dump rolling hopper that is adapted to completely empty itself of all 20 the material contained therein no matter whether the same is dry or wet. This is particularly advantageous when the hopper is to be used for carrying concrete mixtures in either their dry condition or when 25 the water is mixed therewith.

It is also a purpose of the invention to provide a dumping hopper that is so constructed that the same will roll automatically to discharge position, even though it 30 is only partially filled. This is of particular advantage when the hopper is to be used for conveying a charge of concrete, or dry aggregate before water is added thereto and also after the water is added so as to 35 make a wet mixture. It is customary in concrete work to measure the amount of concrete poured by the amount of dry aggregate used. Consequently it is desirable that a vehicle body carrying and 40 adapted to dump automatically, for example, $\frac{1}{4}$ of a cubic yard or dry aggregate, be also adapted to carry and dump automatically $\frac{1}{4}$ of a cubic yard of dry aggregate when mixed with water. The addition 45 of the water causes a material shrinkage in the bulk of the mixture, and ordinarily this shrinkage is so great that the ordinary rolling hopper will not roll to discharge position automatically, due to the lowering of 50 the center of gravity of the load. It is also impossible to fill the rolling hopper completely with the wet mixture, as the same would spill due to the motion of the vehicle, while the same is moving if so 55 filled. The ordinary rolling hopper will

not dump however if only partially filled. The hopper of the present invention is constructed to overcome these difficulties, by providing a very wide flowing mouth for the same and by making the upper portion 60 of much greater area than the base portion thereof.

It is a further object of the invention to provide a hopper having no sharp corners or angles on the interior thereof, and having a long sloping end portion to prevent lodging of wet materials thereon when the hopper is dumped. 65

It is a further object of the invention to provide new and improved locking means 70 for hoppers, which locking means will hold the hoppers in their normal load carrying position and will also act as an actuating means to release the locking mechanism.

Other objects and advantages of the invention will appear as the description of the accompanying drawings showing one form that my invention may take, proceeds. In showing only one form of the invention I desire to have it understood that this is 75 merely done for purposes of illustration and that I do not intend to limit myself to the exact details shown and described, but desire to include in my invention all modifications or changes that would suggest 80 themselves to anyone skilled in the art and which would fall within the scope of the claims. 85

In the drawings:

Fig. 1 is a longitudinal vertical sectional view of a portion of the vehicle showing the rear dump rolling hopper and the parts 90 cooperating therewith;

Fig. 2 is a transverse section taken on the line 2—2 of Fig. 1; 95

Fig. 3 is a horizontal section taken on the line 3—3 of Fig. 1;

Fig. 4 is a section taken on the line 4—4 of Fig. 3, on an enlarged scale, and;

Fig. 5 is a section taken on the line 5—5 100 of Fig. 3, also on an enlarged scale.

Referring in detail to the drawings the invention comprises a pair of longitudinally extending supporting rails 6 preferably made in the form of an I-beam and secured by means 105 of any suitable securing devices, such as the U-bolts 7 and 7' to the vehicle framework 8. The rails 6 are provided with downwardly extending portions 9 and pivot members 10 made in the form of hook shaped brackets 110

having a socket portion 11 with one of the webs of the I-beam constituting the rail forming a projecting guard member 12 for the same. Adapted to cooperate with the 5 rails 6 is a hopper 13 which is provided with rails 14 that are adapted to cooperate with the rails 6 having curved portions 15 which are adapted to cooperate with the downwardly inclined portions 9 of the rails 6 as 10 the hopper 13 rolls toward the inclined portions and pivot pins 16 that are adapted to cooperate with the sockets 11 in the pivot members 10 to provide for a final pivotal dumping movement of the hopper 13, the 15 pivot pins 16 being located at the junction of the straight portions of the rails 14 and the curved portions 15 thereof. The hopper 13 is provided with a short flat bottom portion 17, straight vertical side walls 18 and 20. The front end wall 19 and rear end wall 20. The front end wall 19 is inclined slightly from the vertical to flare outwardly slightly toward the top of the hopper, the end wall 19 being substantially straight from the top 25 to the bottom thereof and joining the bottom portion of the hopper by means of a portion having a gradual curvature as shown at 21. The rear end wall 20 is inclined relatively to the bottom portion 17 at substantially an angle of 45 degrees so as to provide a long sloping rear end wall that provides a long over-hanging portion extending rearwardly beyond the short bottom portion or base portion 17. The rear end wall 20 is 30 substantially straight from the top to the bottom thereof and joins the base portion 17 of the hopper by a portion 22 having a gradual curvature. It will thus be seen that a hopper is provided having an interior that 35 has no sharp corners and that has no pockets therein in which any loose material will lodge itself when the hopper is dumped. This is especially advantageous when a wet mixture, such as wet concrete, is dumped 40 from the hopper 13, as this is very liable to stick in any angles or corners that exist in the hopper.

It will also be noted that the hopper has a substantially straight upper edge 23, the 45 upper edge of the members 18 and the end portions 19 and 20 being substantially in the same horizontal plane when the hopper is in the load carrying position shown in Fig. 1. This is advantageous when a liquid or semi-liquid material is carried in the 50 hopper thus preventing spilling of the same. The hopper is of such proportion that when the same is fully loaded it will roll automatically from the position shown in Fig. 1 to 55 the dumping position down the inclined portions 9 of the rails and pivot on the pins 16, thus completely dumping the contents of the hopper 13. The hopper will also automatically discharge the contents thereof in 60 the same manner, even though only partially 65

filled, as would be the case when filled with a wet concrete mixture that would completely fill the hopper before the water is added thereto. When this is done the hopper will be approximately four-fifths filled and 70 will roll to the discharge position as readily as though completely filled due to the long sloping rear end wall of the hopper.

In carrying materials that are in a fluid or semi-fluid state, it would be impossible 75 to entirely fill the hopper, as some of the material would be spilled, due to the motion of the vehicle if it were completely filled. This, however, offers no disadvantage in the present form of hopper as the same will roll 80 automatically to discharge position even if only filled to such an extent that the contents will not spill.

In order to hold the hopper firmly in its load carrying position the brackets 24, having the portions 25 against which the forward end portions 19 of the hopper may rest, are provided. These cooperate with the straight portions of the rails 6 and the flat bottom portions 17 of the hopper to 90 brace the same in its load carrying position. However, locking means have to be provided to prevent the hopper from rolling down the inclined runway to the discharge position. The locking means used may comprise a bail 26 pivotally mounted in the rails 6 in any suitable manner and having a horizontally extending portion 27 that is adapted to engage with the hook members 28 mounted in any suitable manner on the 100 forward end portion 19 of the hopper, the portions 27 of the bail resting in a groove or recess 29 in the hook members 28.

In order to guard against any possible disengagement of the hooks 28 and bail 27, 105 due to jarring of the vehicle when traveling over the roads, a locking lever 30 is provided. The locking lever 30 is mounted centrally of the forward end portion 19 being pivotally mounted between a pair of ears 31 110 on said forward end portion 19 and having a hook portion 32 provided with a recess 33 to receive the portion 27 of the bail. The locking lever 30 is provided with an operating handle portion 34 and with a rearwardly extending portion 35 that is adapted to engage the forward end wall 19 of the hopper to limit the downward movement of said lever. Between the extension 35 and the socket or recess 33 the lever is provided 115 with a cam face 36 that cooperates with the portion 27 of the bail to lift the same out of the recesses 29 formed in the hook members 28 when the lever 30 is swung in a clockwise direction as shown in Fig. 4, the lever 120 30 thus serving both as an additional locking means and as a release mechanism for the locking bail.

In order to limit the swinging movement of the hopper toward dumping position the 130

flexible member 37 provided with the yieldable connection member 38 is employed, the flexible member 37 being secured to the hopper in any suitable manner as by the eye 39, and the yieldable member 38 being secured to the runway in any suitable manner as to the ears 40 as shown in Fig. 1. Secured to the rear end wall of the hopper is the yieldable member 41 and attached thereto 5 the flexible member 42 which is suitably secured to the runway. The members 41 and 42 are of such a length that in the normal position of the hopper the spring 43 of the flexible member 41 is under tension, therefore 10 when the bail member 25 is released from the hooks 28 by raising the locking lever, the spring 41 will tend to start the hopper toward its dumping position. This movement is assisted by the load contained 15 within the hopper and also by means of the hopper itself, which is so constructed that the center of gravity of the load and the hopper acts through a line to the rear of the top end of the inclined sections of the rails 20 either when the hopper is fully loaded or when partially loaded as previously outlined.

In order to dislodge the wet concrete mixture from the hopper it is necessary that the 25 hopper dump fast enough that the upper portion of the material does not slide off first and discharge part of the load only. In the present invention the hopper rolls rapidly to discharge position and the stop 30 chains are suddenly drawn taut as the hopper goes through its final pivotal movement, checking the movement of the hopper with a sudden impact dislodging the entire load at once. The entire discharge movement of 35 the hopper may thus be described as comprising a rolling movement on the runway, followed by a pivoted movement about the pivot hooks and terminating in a final impact that discharges the load.

40 Having thus described my invention what I claim as new and desire to secure by U. S. Letters Patent is:

1. A device of the character described comprising a runway and a rear dumping 45 hopper adapted to roll on said runway from charge carrying to discharge position, said hopper comprising a flat base portion and straight inclined end wall joined to said base portion by portions having a smooth, 50 gradual curvature to avoid all sharp corners in said hopper, the rear end wall of said hopper being relatively long and being inclined substantially at an angle of 45 degrees to said bottom portion, said hopper being 55 so constructed that the same has a progressively increasing tendency when fully loaded and when only partially loaded to roll substantially automatically from charge carrying to discharge position.

60 2. A device of the character described com-

prising a runway, a hopper adapted to roll on said runway, a hook member extending from one wall of said hopper, a bail member supported by said runway and adapted to engage said hook member to maintain the 70 hopper in normal position, and a locking lever pivoted on said hopper adapted to engage said bail to lock said bail in hopper holding position.

3. A device of the character described 75 comprising a runway, a hopper adapted to roll on said runway, a hook member extending from one wall of said hopper, a bail member supported by said runway and adapted to engage said hook member to 80 maintain the hopper in normal position, and a locking lever pivoted on said hopper adapted to engage said bail to lock said bail in hopper holding position, said locking lever being adapted to disengage said bail 85 from said hook, when moved to unlocking position.

4. A device of the character described comprising a runway, a hopper adapted to roll on said runway, a hook member extending from one wall of said hopper, a bail member supported by said runway and adapted to engage said hook member to maintain the hopper in normal position, and a locking lever adapted to engage said bail 90 to lock said bail in hopper holding position, said locking lever being provided with a cam portion adapted to engage said bail and release the same from said hook, when said lever is moved to unlocking position. 100

5. A device of the character described comprising a runway, a hopper adapted to roll on said runway, a hook member extending from one wall of said hopper, a bail member supported by said runway and adapted to engage said hook member to maintain the hopper in normal position, and a locking lever adapted to engage said bail to lock said bail in hopper holding position, 105 said locking lever having a hook portion to engage said bail and a cam portion adapted to engage said bail to release the same from said first mentioned hook, when said lever is moved to unlocking position. 110

6. A device of the character described 115 comprising a runway, and a one way dumping hopper adapted to roll on said runway, said hopper comprising a short substantially flat bottom portion upon which said hopper is adapted to rest in load carrying position, front and rear end walls and side walls having their top edge portions lying substantially in a horizontal plane when said hopper is in load carrying position, said front end wall being slightly inclined to the vertical and said rear end wall being inclined at a much greater angle to the vertical providing a long rearwardly overhanging tapering nose portion, the proportion of said nose portion to the remainder of said hop- 120 125 130

- per being such that said hopper has a progressively increasing tendency both when fully and when only partially loaded to roll substantially automatically from load carrying to discharge position as the same moves from load carrying to discharge position, to discharge the contents of said hopper therefrom as one mass.
7. A device of the character described comprising a vehicle framework, said framework being provided with a substantially flat support, a one-way dumping hopper mounted on said framework, a runway along which said hopper is adapted to roll, said hopper having a substantially flat bottom portion conforming to said flat support and resting thereon in normal load carrying position and straight inclined end walls, one of said end walls being provided with means adapted to cooperate with an inclined portion of said runway, cooperating pivot members on said hopper and said runway, and a flexible limiting member connected to said framework and to said hopper, said hopper being so constructed that the same will have a progressively increasing tendency to roll substantially automatically from load carrying to discharge position, as the same rolls toward the discharge end of said runway both when fully and when partially loaded, said rolling movement terminating in a pivotal movement about said pivot members and said limiting member being adapted to check the pivotal movement of said hopper with a sudden impact to dislodge the contents thereof so that the same will be discharged in a body.
8. A device of the character described comprising a vehicle framework, said framework being provided with a substantially flat support, a one-way dumping hopper mounted on said framework, a runway along which said hopper is adapted to roll, said hopper having a substantially flat bottom portion conforming to said flat support and resting thereon in normal load carrying position and having a portion adapted to cooperate with an inclined portion on said runway when said hopper rolls to discharge position, said hopper being so constructed that the same has a progressively increasing tendency both when fully loaded and when partially loaded to roll substantially automatically from load carrying to discharge position to discharge the contents of said hopper therefrom as one mass.
9. A device of the character described comprising a vehicle framework, said framework being provided with a substantially flat support, a one-way dumping hopper mounted on said framework and a runway along which said hopper is adapted to roll, said hopper having a short substantially flat portion conforming to said support and resting thereon in normal load carrying position and having a portion adapted to cooperate with an inclined portion on said runway when said hopper rolls to discharge position, said hopper being so constructed that the same has a progressively increasing tendency both when fully loaded and when partially loaded to roll substantially automatically from load carrying to discharge position to discharge the contents of said hopper therefrom as one mass.

In witness whereof, I hereunto subscribe my name this 16th day of July, A. D. 1920.

ALBERT P. LEE.
